PAN CLEANING AND GREASING MACHINE.

1,153,683.

Specification of Letters Patent. Patented Sept. 14, 1915.

Application filed June 9, 1915. Serial No. 33,032.

To all whom it may concern:

Be it known that I, Hugo GOTTSCHALK, a citizen of the United States, residing at Reedsville, county of Mifflin, State of Pennsylvania, have invented a new and useful Pan Cleaning and Greasing Machine, of which the following is a specification.

My invention relates to a new and useful pan cleaning and greasing machine and consists of a plurality of brushes with means for reciprocating the same whereby, when the pans are placed thereover, the brushes serve to clean and grease the same, said brushes being adjustably mounted in order 15 that they may be varied with respect to each other.

It further consists in forming the brushes with the bristles extending from the edges only and not from the upper faces thereof, 20 so that only the sides and ends of the pan will be greased.

It further consists of novel features of construction, all as will be hereinafter fully set forth.

For the purpose of illustrating my invention, I have shown in the accompanying drawing one form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 is an end elevation of a machine embodying my invention, partly in section. Fig. 2 is a side elevation thereof. Fig. 3 is a sectional view on line $x-x$, Fig. 2, partly broken away. Figs. 4 and 5 are sectional views showing forms of brushes which may be employed. Fig. 6 is a side elevation of a standard or spindle employed 45 in detached position.

Similar numerals of reference indicate corresponding parts in the figures.

Referring to the drawings, 1 designates the frame of the machine which may be of any suitable or desired construction and upon which the various parts of the machine may be suitably and properly mounted and related, in order to operate in the desired manner.

2 designates a shaft mounted in the bear-

ings 3 carried by the frame 1 which shaft is adapted to be rotated in any suitable or desired manner. In the present instance, I have shown a motor 4, on the shaft 5, of which, is a gear 6 which is in mesh with 60 the gear 7 mounted on the shaft 2.

8 designates a reciprocating member movably supported by the frame 1 said member being here shown as a plate which is suitably connected with bars 9 at its opposite 65 end which bars are suitably connected with the guide members or shoes 10 suitably spaced from each other and retained in this relation by the bars 9. The bottom wall of each of the members 10 is provided with a 70 recess to receive and slide on the tracks or guides 11 carried by or on the frame 1. As shown I have provided extensions 10^a at the lower portion of the bearing members 10 to increase the bearing surface. It will 75 be understood that the said guide members 10, bars 9 and plate 8 are suitably connected in order to be actuated together. Any suitable means for reciprocating the parts may 80 be employed. As here shown, I have provided a cam 12 in suitable connection with the shaft 2 and in engagement with said cam 12 is a cam-strap 13 which is connected with a rod 14 which is in pivotal engagement with an arm 15 connected with one 85 of the guide members 10, it being understood more particularly from Fig. 1 that there is a cam 12 and its coacting parts at each side of the machine to insure proper reciprocation.

Carried by the reciprocating member or plate 8 is a plurality of brushes which are adjustable upon the plate laterally of the direction of movement thereof, in order that the relation of the brushes may be varied depending upon the pans to be cleaned or greased. In the present instance, as will be seen from Fig. 1, there are two series of brushes one series serving to clean the pans and the other for greasing the same. In 100 order to adjust the brushes I have here shown the plate 8 as provided with the laterally extending slot or slots 16 and in said slots are a plurality of spindles or standards 17 which are provided with locking means in order that each standard may be individually released or adjusted. As shown, the standards are provided with shoulders 18 which engage the upper face 105 of the plate 8 and I provide lock nuts 19 110

to engage with the threaded portion 20 of the spindle, which nuts engage with the bottom face of the plate 8 when it is desired to secure or lock the spindles in position. The upper end of each standard is provided with a tapered portion or end 21 which is adapted to receive or hold a brush. As will be understood from Figs. 4 and 5, I desire to shape the brushes or brush heads 10 to conform to the shape of the interior of the pans to be cleaned and I provide each brush head 22 with a tapered socket 23 which is adapted to receive the tapered end 21 of a spindle in order that the brushes 15 will be securely held in place and in order that the pressure of the pans when in operative position will assist in holding the parts in suitable relation.

The brush heads may be provided with 20 bristles depending upon the work to be accomplished. Thus in Fig. 5 I have shown bristles 24 which extend laterally from the sides and ends only of the brush head and which serve to engage the sides and ends 25 only of the pans, the upper side of the brush heads being free from bristles so that the bottom of the pans will not be greased. In Fig. 4 in addition to the bristles 24 I have shown bristles 25 projecting upwardly 30 from the upper face of the brush heads to engage with the bottom of the pans to grease that portion thereof if desired. It will be understood that in the baking of bread it is customary to take a plurality of the pans 35 26 and to connect the same together in any suitable manner, as by the bars 27, forming a nest of pans located side by side and any number of these pans may be so connected as desired, it only being necessary in my 40 machine to provide the same number of brushes, or standards with the brushes thereon, as there are pans in a nest. As will be seen in Fig. 1, I have shown four pans suitably connected and a corresponding number 45 of standards and brushes but the number may be varied as desired.

The operation of the device is as follows: Motion being imparted to the shaft 2 through the medium of cam 12 and cam-strap 13 the plate 8 will be suitably recipro- 50 cated on the frame 1 of the machine, it being understood that the brush heads 22 corresponding to the shape of the pans to be cleaned are previously placed upon the standards 17 and that the standards have been adjusted in their position laterally of the movement of the plate 8 in order to be suitably located to enter the pans when placed thereon. The operator by inverting 55 the pans and lowering the same, will cause the brush heads 22 of the cleaning series of brushes to enter the pans and the recipro- 60 cation of the brush heads back and forward will properly clean the pans, after which he 65 removes the pans from the cleaning brushes

and places them over the greasing brushes and the reciprocation of these brushes in the pans will properly grease the same.

If the nest of pans vary, that is, in number, or if the space between the pans to be cleaned differs for various nests of pans, the operator can release the locking nut 19 and adjust the standards 17 to their proper place and again lock them ready for operation. I have found that in some instances it is not desired to grease the bottom of the pan but only the sides and ends and when such action is desired, I employ the form of brush head shown in Fig. 5, and if the brush heads then on the standards 70 are of the construction shown in Fig. 4, it is necessary to remove these from the standards and substitute therefor the form desired, as for example, as shown in Fig. 5, 75 wherein the bristles extend from the sides and end only of the brush heads so that when the pans are placed on the brushes, the greasing action will only affect the sides and ends of the pans as will be evident.

It will be seen from the above that the 80 brush heads can be quickly and easily removed and replaced and yet will be firmly held in position. The location of the standards on the plate 8 may be quickly and easily varied or adjusted and locked in 85 their adjusted positions so that the machine may be quickly adapted for work on any character of pans. By forming the brushes in shapes to conform to the shape of the pans, they will efficiently accomplish the 90 desired result. It will also be seen, as above described, that I may employ brushes shaped to grease only the sides and ends of the pans, which cannot be done where a circular brush is employed or where a ro- 95 tary movement is imparted to the brush itself, which is not the case in the present instance, since the brushes are stationarily mounted with respect to their supports, that is, the standards, to which the reciprocating 100 movement in a horizontal direction is im- 105 parted.

It will now be apparent that I have de- 110 vised a novel and useful construction of a pan cleaning and greasing machine which embodies the features of advantage enumerated as desirable in the statement of the invention and the above description, and while I have, in the present instance, shown and described preferred embodiments there- 115 of which will give in practice satisfactory and reliable results, it is to be understood that the same are susceptible of modification in various particulars without departing from the spirit or scope of the invention or sacrificing any of its advantages.

Having thus described my invention what I claim as new and desire to secure by Letters Patent, is:—

1. In a device of the character stated, a 120

plurality of standards suitably supported and laterally adjustable with respect to each other, means for reciprocating said standards, and brushes removably mounted on the 5 standards.

2. In a device of the character stated, a reciprocating member, a plurality of standards carried by said member and adjustable laterally of the direction of movement there- 10 of, and brushes for said standards removably mounted thereon.

3. In a device of the character stated, a reciprocating member, means for actuating the same, a plurality of standards carried 15 by said member and adjustably mounted thereon, and brushes for said standards removably mounted thereon.

4. In a pan cleaning and greasing machine a reciprocating member, means for actuating the same, a plurality of standards carried by said member, means for adjusting the positions of said standards, and brushes shaped to conform to the shape of the pans removably mounted on the stand- 25 ards.

5. In a pan cleaning and greasing machine, a reciprocating member, means for actuating the same, a plurality of standards carried by said member, means for adjusting the positions of said standards, and brushes on said standards having bristles 30 extending from their edges and with their upper faces free of bristles.

6. In a pan cleaning and greasing machine, a reciprocating member, means for 35

actuating the same, a plurality of standards carried by said member, means for adjusting the positions of said standards, and brushes on said standards formed to correspond to the shape of the pans and having 40 laterally extending bristles to engage the sides and ends only of the pan.

7. In a pan cleaning and greasing machine, a reciprocating member, a plurality of supports carried by said member, means 45 for adjusting the positions of said supports, brushes removably and stationarily carried by said supports, and means for actuating said member to horizontally reciprocate said supports and the brushes carried 50 thereby.

8. In a pan cleaning and greasing machine, a frame, a guiding track thereon, bearing members slidable on said track, a plate carried by said bearing members and 55 having a slot extending laterally therein, means for reciprocating the plate and bearing members, standards carried by said plate and movable in said slot to adjust the positions thereof, a locking device for each 60 standard for independently securing the same in their adjusted position to the plate, and a brush head for each standard having a socket for receiving the end thereof where- 65 by the brush head is stationarily carried and movable with a standard.
